(57) **CLAIM**

We claim the ornamental design for a drinking glass, as shown and described.

DESCRIPTION

FIG. 1 is a front elevational view of a drinking glass, the rear elevational view being a mirror image thereof;

FIG. 2 is a top plan view of FIG. 1; and,

FIG. 3 is a bottom plan view of FIG. 1.

The ornamental design which is claimed is shown in solid lines in the drawings. The broken lines in the drawings are for illustrative purposes only and form no part of the claimed design.
